FOREIGN PATENT DOCUMENTS

CN 303294740 7/2015

Primary Examiner — Mary Ann Calabrese*Assistant Examiner* — Jennifer L Rempfer(74) *Attorney, Agent, or Firm* — Nadesan Beck P.C.;
David Jones(57) **CLAIM**

The ornamental design for an outdoor blanket, as shown and described.

DESCRIPTION

FIG. 1 is a perspective view of the outdoor blanket, showing our new design.

FIG. 2 is a top view of the blanket of FIG. 1;

FIG. 3 is a bottom view of the blanket of FIG. 1;

FIG. 4 is a right view of the blanket of FIG. 1;

FIG. 5 is a left view of the blanket of FIG. 1;

FIG. 6 is a rear view of the blanket of FIG. 1; and,

FIG. 7 is a front view of the blanket of FIG. 1.

Elements illustrated in broken lines form no part of the claimed design.

1 Claim, 5 Drawing Sheets(56)
